UNITED STATES PATENT OFFICE.

ALEXANDER MCKERLIE, OF HAMILTON, CANADA.

WINDOW-SCREEN.

SPECIFICATION forming part of Letters Patent No. 484,540, dated October 18, 1892.

Application filed April 27, 1892. Serial No. 430,890. (No model.) Patented in Canada March 14, 1892, No. 38,474.

To all whom it may concern:

Be it known that I, ALEXANDER MCKERLIE, a citizen of Canada, residing at Hamilton, in the county of Wentworth, Province of Ontario, Canada, have invented a new and useful Window-Screen, (for which I have obtained a patent in Canada, No. 38,474, bearing date March 14, 1892,) of which the following is a specification.

10 My invention relates to improvements in window-screens, in which a vertical metallic tube or casing having a vertical slot almost its entire length and an adjustable telescopic cover are arranged and devised to contain a vertical roller provided with a screen fabric rolled around said roller that when operated upon the said roller receives a certain tension from a spiral spring which is attached to the upper part thereof, the whole being 15 incased in said vertical tube and its cover; and the objects of my improvements are, first, to provide a fabric window-screen which is capable of extension across any ordinary window-frame or door; second, to afford facilities for the proper adjustment and manipulation of the same, and, third, when preferable to allow the device to be attached to the opposite side of said window-frame, thus being a reversible window-screen. I attain 20 these objects by the mechanism illustrated in the accompanying drawings, in which—

Figure 1 is a front elevation of a window-screen attached to and opened out in position across the framework of a window. Fig. 2 is an enlarged front sectional elevation of the device, showing the screen partially drawn out; and Fig. 3 is an elevation of the detached cover.

Similar letters refer to similar parts throughout the several views.

The framework around the window, as delineated, is indicated by A, in which a window-sash *a* vertically slides.

B is a vertical metallic tube or casing of any desired length and is secured to the said frame by means of the lugs B'. The adjustable telescopic cover E fits over a certain distance, in telescopic fashion, the upper end of said tube and is provided with an inner 45 tube and socket F in a central position, in which the upper shank end of the vertical

roller I is incased. The lower shank end of said roller fits into the socket B', which is situated in the lower end of said tube. The spiral spring S is coiled around said inner 55 tube F of cover E and fastens at its upper stationary end to the upper part or top of said cover at H, and its rotating lower end fastens to the upper part of vertical roller at J, immediately below the lower end of said 60 inner tube. This spiral spring exerts a sufficient rotary power to the vertical roller to enable it to afford the proper tension and firmness to the fabric screen C when drawn out, as delineated in Fig. 1, and force sufficient to draw the said screen back upon its roller when released at its outer rod end D by its button or lug C' from the window-frame. In order to prevent the cover of said tube from moving when tension is upon the spring, 70 one or two suitable right-angled apertures e are provided in the lower end of the cover, which when in position is locked by means of a projecting pin or pins on the upper part of tube to correspond to position of said apertures, thus locking and unlocking by slightly turning the cover, thus allowing the cover to be removed when necessary.

The composition of the screen fabric may be of suitable material to answer the purpose, as described, and the width of the vertical slot C' in tube may be very slight, so as to correspond to the thickness of screen to allow the same to operate freely.

To reverse the screen, it is merely attached 85 to the opposite side of the frame A by means of screws through the said lugs B', as delineated in Fig. 1. The device operates freely on either side of frame, this being an important feature in this device.

Another important feature and element in my improvement is that this screen can be most conveniently applied to any breadth of window and also be maintained at a proper tension; also, the same can be easily adjusted to or removed from and applied to different windows or doors, when necessary, without the least detriment to the general woodwork thereof.

What I claim as my invention, and desire to 100 secure by Letters Patent, is—

The combination, in a reversible window-

screen, of the vertical tube B, having vertical slot C' to act as an opening to allow screen C to operate and provided with lugs B' to fasten said tube to window-frame A, and telescope-cover E, having inner tube with socket F, and the lower socket B² to support vertical screen-roller I, the spiral spring H, its lower

end fastened to said cover at H', the roller-screen C, and its strengthening-rod D, provided with fastening-lug C², substantially as described and set forth.

ALEXANDER MCKERLIE.
